Application January 30, 1930, Serial No. 424,697
Renewed September 21, 1934

19 Claims. (Cl. 123—179)

This invention relates to starting mechanism for internal combustion engines.

One of the objects of the invention is to provide a novel starting mechanism embodying an inertia member and an internal combustion engine for accelerating said inertia member to store energy therein for cranking an engine to be started.

Another object is to provide a novel starting mechanism embodying an inertia member, an internal combustion engine for accelerating said inertia member, and means for manually cranking said engine to start the same.

Another object is to provide starting mechanism of the type embodying an inertia member and an internal combustion engine for accelerating the same, wherein said engine is automatically stopped when the energy stored in said inertia member is applied to the main engine to be started.

Another object is to provide starting mechanism for an internal combustion engine embodying an inertia member, an internal combustion engine for accelerating said inertia member, and a magneto which provides ignition current for the accelerating engine and also serves as a booster magneto for the main or large engine to be started.

A still further object is to provide starting mechanism for an internal combustion engine embodying an inertia member, a magneto, and means operable at a predetermined speed of rotation of said inertia member to engage the starting mechanism automatically with the main engine to be started and to connect the magneto automatically with said main engine to serve as a booster magneto therefor.

Another object is to provide starting mechanism for internal combustion engines of the type embodying an inertia member, an internal combustion engine for accelerating the same and a magneto providing ignition current for the accelerating engine, wherein the accelerating engine is automatically stopped when the energy stored in the inertia member is applied to the main engine to be started, but the magneto is driven from the inertia member and is adapted to serve as a booster magneto for the engine to be started.

These and other objects will appear more fully hereinafter.

One embodiment of the invention is illustrated in the accompanying drawings, but it is to be expressly understood that said drawings are for purposes of illustration only, and are not to be construed as a definition of the limits of the

invention, reference being had to the appended claims for this purpose.

In said drawings—

Fig. 1 is a longitudinal section through a starting mechanism embodying the invention; one of the planet pinions being omitted in order to avoid obscuring the showing of the adjacent parts;

Fig. 2 is a section taken on the line 2—2 of Fig. 1;

Figs. 3, 4, and 5 are perspective detail views of parts of the mechanism shown in Fig. 1;

Fig. 6 is a section taken on the line 6—6 of Fig. 2; and

Fig. 7 is a wiring diagram.

Referring now to the drawings, wherein like reference characters refer to like parts throughout the several views, and particularly to Fig. 1, the starting mechanism is housed in a sectional casing 1 of any suitable form, the casing sections being secured together in any suitable manner and the inner casing section being provided with a flange 2 that is secured to the housing 3 of an internal combustion engine to be started in any suitable manner, as by means of screws 4. Extending across the casing and preferably formed integrally with one of the casing sections is a plate or diaphragm 5 that is provided with a suitable bearing boss 6 wherein the hub 7 of a flywheel 8 is rotatably mounted in any suitable manner, as by means of ball bearings 9 held in place by a suitable retaining ring 10. A short shaft 11 extends through the hub 7 of the flywheel and is suitably keyed thereto at 12, a collar 13 on said shaft and a lock nut 14 on the outer end thereof preventing relative longitudinal displacement of shaft 11 and hub 7.

Flywheel 8 is preferably of small size and light weight and is adapted for rotation at very high speed, the energy stored in the rapidly rotating flywheel being transmitted preferably through a train of reduction gearing and a yieldable driving connection to a driving member adapted to engage a member of an engine to be started. In the form shown, gear teeth formed integrally with the inner end of shaft 11 constitute a pinion 15 that meshes with a gear 16 which is rotatably mounted by means of a stub shaft 17, preferably formed integrally therewith, in ball bearings 18 carried by a boss 19 formed in the plate or diaphragm 5. The inner end of shaft 17 is provided with gear teeth constituting a pinion 20 that meshes with an internal ring gear 21, the hub 22 of which is rotatably mounted on an extension 23 of a barrel member 24 that is in turn rotatably mounted in the housing by suitable means such as

ball bearings 25. The hub 22 of ring gear 21 is provided with gear teeth and constitutes a pinion or sun gear that meshes with a plurality of planetary gears, one of which is shown at 26 in Fig. 1, 5 said planetary gears preferably being three in number and being rotatably mounted on the barrel 24 in any suitable manner, as by means of bushings 27 surrounding screws 28 threaded into said barrel member. A retaining ring 29 secured 10 to the screws 28 retains the planetary gears on the bushings 27, and an internal ring gear 30 that is secured to the casing by means of screws 31 surrounds and meshes with said planetary gears.

The rotation of flywheel 8 is thus transmitted 15 through a reduction gear train constituted by pinion 15, gear 16, gears 20, 21, sun gear 22, planetary gears 26 and ring gear 30 to the barrel 24. The rotation of barrel 24 is in turn suitably transmitted, preferably through a yielable driving 20 connection, to a driving member or clutch jaw 32 that is adapted to be shifted axially into driving engagement with a corresponding clutch jaw 33 formed on a member of the main engine to be 25 started. In the form shown, an interiorly threaded nut 34 is positioned in the barrel 24 and is drivably connected therewith by means of a friction clutch formed by a plurality of friction disks 35, alternate disks being splined to the inner 30 surface of barrel 24 and to the outer surface of nut 34. The disks 35 are held between a spacing ring 36 that is interposed between the outermost disk and the barrel 24 and a spacing ring 37 that is interposed between the innermost disk and a collar 38 formed on the nut 34, and are resiliently 35 pressed together by means of a plurality of coil springs 39 that are interposed between collar 38 and spacer 37 and a nut 40 that is threaded in the outer end of barrel 24. If desired, a ring 41 provided with a plurality of studs 42 may be 40 employed to maintain springs 39 in spaced relation around the axis of the nut and barrel.

A short shaft 43 positioned within the nut 34 is exteriorly threaded to engage the threads formed 45 on the interior of the nut, the outer end of said shaft being splined to engage the interiorly splined hub 44 of clutch jaw 32. A rod 45 extends centrally through the extension 23 of barrel 24, shaft 43 and clutch jaw 32 and is provided on its 50 inner end with a nut 46, a coil spring 47 surrounding said rod and being interposed between the outer face of clutch jaw 32 and shaft 43. Rod 45 is further provided with a shoulder 48 engaging the outer end of shaft 43, so that when said rod is 55 pushed toward the left, as seen in Fig. 1, by means described hereinafter, the threaded engagement between shaft 43 and nut 34 causes said shaft to move toward the left, compressing spring 47 and resiliently urging clutch jaw 32 inwardly into engagement with clutch jaw 33. When the engine 60 to be started starts under its own power, clutch jaw 33 overruns clutch jaw 32 and the inclined faces of the teeth of said jaws are adapted to force clutch jaw 32 outwardly or to the right, as seen in Fig. 1, and to restore the parts to the position 65 shown in the drawings.

It is desirable to employ an internal combustion engine to accelerate the flywheel 8 to the proper speed before the clutch jaws 32 and 33 are engaged, and preferably this accelerating engine is drivably connected with the flywheel 8 through suitable gearing and also through a one-way driving connection so that the flywheel is driven by the engine but energy will not be transmitted from the flywheel back to the engine. In 70

the form shown, a two-cycle internal combustion engine of any suitable type is employed which, as shown, comprises the usual cylinder 49 and liner 50 in which reciprocates a piston 51 having a wrist pin 52 to which is pivoted a connecting rod 53. A crank pin 54, on which the end of the connecting rod 53 is rotatably mounted by means of a suitable roller bearing 55 and secured by means of a disk 56 and nut 57, is secured to or preferably formed integrally 10 with a crank or disk 58, the hub 59 of which is keyed at 60 to one end of a shaft 61 and is secured on said shaft by a nut 62. Hub 59 is rotatably mounted by means of ball bearing 63 in the casing and constitutes a supporting bearing 15 for one end of shaft 61, and the crankcase of the accelerating engine is sealed in any suitable manner as by means of a cork washer 64 or the like compressed between a ring or nut 65 threaded on the end of hub 59 and a ring 66 drivably 20 connected to shaft 61 in any suitable manner. A retaining ring 67 secured to the casing in any suitable manner maintains these parts in proper assembled relation. The other end of shaft 61 is mounted in a ball bearing 68 supported in 25 a recess formed in a plate or diaphragm 69 preferably integral with one of the casing sections, and a retaining nut 70 is threaded on the inner end of the shaft.

The shaft 61, which constitutes the crank shaft 30 of the accelerating engine, is adapted to drive the flywheel 8 preferably through a suitable train of step-up gearing and through a suitable one-way driving connection. In the form shown, a gear 71 is mounted on the shaft 61 and is drivably 35 connected therewith by means of an overrunning roller clutch 72 of any suitable type that is adapted to transmit torque in one direction only, that is, the clutch transmits torque from shaft 61 to gear 71 but the latter overruns shaft 61 so that driving torque is not transmitted in the reverse direction. Gear teeth 73, 40 preferably formed integrally with a shaft 74, constitute a pinion that meshes with gear 71, the shaft 74 being rotatably mounted by means of ball bearings 75 supported in the plate or diaphragm 69. 45

Rotation of the shaft 74 is transmitted to flywheel 8 by any suitable means, which as shown, comprise a clutch jaw 76 drivingly secured in any suitable manner to the end of shaft 74 and engaging a corresponding clutch jaw 77 that is suitably attached as by means of rivets 78 to the flywheel 8. Endwise movement of shaft 74 is prevented by clutch jaw 76, a collar 79 engaged between the ball races of ball bearings 75, 55 and a nut 80 threaded on the shaft 74 and having engagement with the outermost ball race.

For the purpose of providing ignition current for the accelerating engine, a magneto 81 of any suitable type is secured in any suitable manner to the casing section and is drivably connected to a rotating part of the mechanism so as to be rotated with the crank shaft 61. Preferably said magneto is adapted by means hereinafter described to provide ignition current not only for the accelerating engine, but also for the main engine to be started by clutch jaws 32, 33, and accordingly the driving connections for said magneto are such that the magneto armature is rotated not only by the accelerating engine, but also by the flywheel 8, although the accelerating engine is stopped.

In the form shown, the shaft of the magneto 81 is drivably connected by means of cooperating clutch members 82, 83 with a shaft 84, which 75

is rotatably mounted by means of ball bearings 85 in the casing 1, and with a gear 86 which is keyed to shaft 84 at 87 and meshes with gear 71 on shaft 61. As above described, gear 71 may be driven by shaft 61 to rotate the flywheel 8, or may be rotated by flywheel 8 and overrun the stationary shaft 61, and the magneto armature is rotated in either case.

Any suitable means may be employed for starting the accelerating engine, said means preferably being manually operable and embodying an engine flywheel. Preferably, however, the driving torque of a manually operable member is transmitted to the accelerating engine through the shaft 84, which as above described, is connected directly with the magneto armature shaft, so that the rotation of the magneto armature may be synchronized with the position of the piston 51 and the accelerating engine will be properly timed. In the form shown, the outermost end of shaft 84 is hollow and is provided with a suitable slot 88 so that the usual hand crank (not shown) may be engaged therewith. Positioned in the hollow shaft 84 is a short rod 89 that is resiliently urged outwardly by means of a suitable coil spring 90, and a pin 91 extends diametrically through the rod 89, through elongated slots 92 formed in the walls of shaft 84, and through the hub 93 of a clutch jaw 94 that is slidable on said shaft. When a hand crank is fitted to the end of shaft 84, rod 89 is pushed inwardly, and clutch jaw 94 is displaced longitudinally on the shaft 84 into engagement with a corresponding clutch jaw 95 that is suitably secured as by means of screws 96 to a gear 97, the latter being mounted for rotation on shaft 84 by means of a suitable bushing 98 and meshing with a gear 99 that is keyed at 100 to shaft 61. A flywheel 101 is suitably secured to a flange 102 formed on said gear 97 by means of screws 103. Thus when a hand crank is fitted to the end of shaft 84 and the shaft together with the magneto armature is rotated, clutch jaws 94, 95 are engaged and the rotation of shaft 84 is transmitted through gears 97 and 99 to crank-shaft 61 to start the accelerating engine, flywheel 101 rotating simultaneously.

It will be seen that the relation between the angular position of the magneto armature and the position of piston 51 is controlled by the engagement of clutch jaws 94, 95, and said jaws are preferably of a type engageable in only one relative position. As shown in Fig. 4, clutch jaw 94 is provided with two notches 204 that are engaged by teeth 205 formed on clutch jaw 95, and the driving faces of said notches 204 and teeth 205, instead of being diametrically opposite one another, are slightly offset so that they are engageable in only one relative position. Therefore, no matter what may be the relative positions of the magneto armature and the piston 51 when the shaft 84 is first turned by the hand crank, the driving connection from the hand crank to the crank shaft 61 will be established in only one predetermined relative position of the shafts 84 and 61 so that the accelerating engine will always be properly timed.

When the flywheel 8 is rotating and the clutch jaws 32 and 33 mesh, slippage results between the friction disks 35 and the flywheel 8 slows down as the energy stored therein is absorbed in turning over the engine to be started, and simultaneously with the engagement of said clutch jaws it is desirable that the accelerating engine be stopped. At this time the magneto 81, which is still rotated by the flywheel 8, is available for

use as a booster magneto for the engine to be started. Accordingly, novel means may be provided that are operated in common with the means for displacing the rod 45 to mesh the clutch jaws 32, 33 and which disconnect magneto 81 from the accelerating engine and connect it with the main engine to be started, thereby both stopping the accelerating engine and employing the magneto as a booster. While any suitable means may be employed for this purpose, either manually or automatically operable, it is preferred to employ automatic means operable when the flywheel 8 has reached a predetermined speed for shifting rod 45 and for simultaneously operating suitable switching mechanism controlling the circuit of the magneto 81. In the form shown in the drawings, said automatic means is constituted by a governor mechanism operated by centrifugal force and carried by shaft 74 that is drivingly connected with flywheel 8 to accelerate the latter.

Referring more particularly to Figs. 1, 2, 3, and 6, the shaft 74 is provided with a straight splined portion 104 on which is mounted the correspondingly splined hub 105 of a plate 106, said hub 105 seating against a collar 107 formed on shaft 74. A plate 108, that is mounted on the hub 105 and is suitably secured to plate 106, as by means of a rivet or rivets 109, is provided with diametrically opposite extensions in which are formed elongated slots 110. The end of shaft 74 is provided with curved splines or threads 111 on which is positioned a correspondingly splined or threaded hub 112 having a circular flange or plate 113 intermediate its end and a flange or collar 114 formed on its outer end.

A pair of similar irregularly shaped flyweights 115, provided with forked or bifurcated ends 116 and 117, are each pivoted at diametrically opposite points to the flange 113 by suitable means such as pins 118 extending through the bifurcations 116 and preferably riveted in the flange 113. Pins 119 extend through and are preferably riveted in the bifurcations 117 of each of members 115, and said members 115 are resiliently held inwardly close to the shaft 74 by means of coil springs 120, each extending from a pin 119 of one member 115 to a pivot pin 118 of the other member 115. Flyweights 115 are positioned intermediate the flange 113 and plate 106, and each flyweight is provided adjacent the center of its outer periphery with a hole or opening 121 in each of which is positioned one end of a pin 122, the other ends of said pins 122 extending through the slots 110 in the plate 108. Pins 122 normally rest in the inner ends of slots 110, and the plate 108, flyweights 115, and the member 112 and its flange 113 normally rotate together in unison with the shaft 74. When the speed of rotation of shaft 74 becomes sufficiently great that the tension of springs 120 is overcome and the weights 115 move radially outward, pins 122 moving outwardly in slots 110, relative rotation is produced between member 112 and plates 106 and 108, that is, between member 112 and shaft 74, and the splines or threads 111 cause member 112 to move longitudinally toward the end of shaft 74.

This longitudinal displacement of the member 112 may be employed to operate the rod 45 and the switching mechanism above referred to by any suitable means. As shown in the drawings, a shaft 123 is rotatably mounted in a bearing 124 formed in the casing and carries at its inner end a fork 125, the bifurcations of which engage in the groove formed on member 112 by the flanges or collars 113, 114. Fork 125 is retained on shaft

123 by means of a nut 126 threaded on the lower end of the shaft. When the member 112 moves longitudinally on the shaft 74, as above described, fork 125 causes shaft 123 to rotate and this rotation is transmitted by an arm 127 (Fig. 5) rigidly secured to the outer end of shaft 123 and a link 128 to an arm 129 rigidly secured to the outer end of a rotatable shaft 130. As shown in Fig. 2 the link 128 is disposed outside the casing 1, and 10 accordingly the arm 129 and the outer end of shaft 130 which connects therewith (as shown in Fig. 5) are also disposed outside the casing. A fork or bifurcated member 131, rigidly secured to the inner end of shaft 130 in any suitable manner as by means of a pin or set screws 132, embraces the rod 45 and engages a pin 133 extending through said rod. When the flywheel 8 and shaft 74 reach a predetermined speed of rotation, and the flyweights 115 move radially outward, the forks 125 and 131 operate through the connections above described to move the rod 45 longitudinally toward the left as seen in Fig. 1, thereby displacing clutch jaw 32 into engagement with clutch jaw 33, as above described.

25 The displacement of member 112 and the resulting rotation of shaft 123 is further adapted to operate a suitable switching mechanism controlling the circuit of the magneto 81. In the form shown, a terminal block 134 of suitable insulating material is secured to the casing and carries a plurality of terminals that are interconnected by means of a switching arm 135 of suitable insulating material that is rigidly secured to and rotates with the shaft 123. Preferably the terminal block 134 is provided with a curved guide plate 136 (Fig. 5) with which cooperates a correspondingly shaped guide plate 137 carried by the arm 135. Terminal 138 is connected with the terminal of the magneto 81 and is provided 30 with a spring pressed contact 139 (Fig. 1) engaging an arcuate plate 140 of conducting material that is carried by arm 135. An extension 141 of said plate 140 is provided with an upwardly turned contact 142 adapted to engage either a terminal 143 leading through the usual 35 distributor to the ignition circuit of the main engine to be started, or a terminal 144 that is connected to the ignition circuit of the accelerating engine according to the position of the 40 switch arm 135.

The operation of the apparatus is as follows. When it is desired to use the starting mechanism, a hand crank is fitted to the end of shaft 84 and rotated until clutch jaws 94 and 95 are 45 engaged. The hand crank is now drivingly connected with magneto 81 and through gears 97 and 99 with the crankshaft 61 of the accelerating engine, the magneto and the piston of the accelerating engine being properly related with regard 50 to the timing of the engine. Member 112 is in its normal position shown in the drawings with the rod 45 retracted and the switch arm 135 positioned to connect terminals 138 and 144. Rotation of the hand crank is transmitted to the magneto, the accelerating engine and the flywheel 101 to start the small accelerating engine. As soon as the accelerating engine starts, the inclined faces of teeth 205 and the spring 90 55 disengage the hand crank from driving relationship with the mechanism. The rotation of crankshaft 61 is transmitted through the overrunning clutch 72 to the gear 71, and thence through gear 86 to the magneto 81 and through pinion 73, shaft 74, and clutch faces 76, 77 to the flywheel 8. The flywheel 8 drives through the

reduction gearing above described and through the friction clutch 35, the nut 34, shaft 43, and clutch jaw 32.

As soon as flywheel 8 has reached a predetermined speed of rotation, the flyweights 115 move radially outward and cause relative rotation between the member 112 and shaft 74, whereupon the member 112 moves outwardly or to the right as seen in Fig. 1 to actuate the shifting mechanism above described. Rotation of switch arm 135 disconnects the terminals 138 and 144 so that the accelerating engine stops, and connects the terminals 138 and 143 so that the magneto 81, which is now driven by the flywheel 8 through gears 73, 71 and 86, is connected to the ignition circuit of the engine to be started. At the same time shifting fork 131 pushes rod 45 inwardly or to the left as seen in Fig. 1, and shoulder 48 on said rod engages the shaft 43 and causes relative rotation between the shaft and nut 34 which in turn causes said shaft to move inwardly or to the left in said nut until a stop nut 145 on said shaft engages a suitable shoulder 146 formed interiorly of said nut. Spring 47 which tends to be compressed by movement of the shaft 43 now urges clutch jaw 32 resiliently into engagement with clutch jaw 33.

As soon as the engine starts under its own power, clutch jaw 33 overruns clutch jaw 32 and the inclined faces of the teeth of said jaws are effective to cause clutch jaw 32 to move outwardly, coacting with spring 47 to restore the parts to the position shown in the drawings. As the speed of the flywheel decreases and the flyweights tend to return to their initial position, the automatic shifting mechanism tends to be returned to its initial position ready for another starting operation and any suitable resilient means may be employed if desired to assist the return movement of the shifting mechanism.

The above apparatus provides novel starting mechanism for internal combustion engines wherein an inertia member is rapidly rotated to store energy therein which may be employed to crank the engine to be started and wherein a small and easily cranked internal combustion engine is employed to accelerate the inertia element to the proper speed. A booster magneto is provided which serves both as a magneto for the accelerating engine and as a booster magneto for the engine to be started. Novel means are provided for starting the accelerating engine manually wherein the magneto and the accelerating engine are drivably connected with the manual starting means, with the magneto in a predetermined angular position relative to the position of the piston of said engine to insure proper timing. Moreover, means are provided whereby when the flywheel or inertia member reaches the proper predetermined speed, the accelerating engine is automatically stopped and disconnected from the flywheel, while at the same time the magneto continues to be driven by the inertia element and is automatically connected to the engine to be started to serve as a booster magneto therefor.

While only one embodiment of the invention has been described and illustrated in the drawings, it will be apparent that the invention is capable of a variety of mechanical forms. The inertia member and the driving transmission between the same and the engine engaging or driving member may be changed or replaced by equivalent means, and means other than those shown may be employed for operating the clutch shifting and switch mechanism when the inertia element reaches a predetermined speed. The means

for connecting the magneto with the engine to be started to serve as a booster magneto may be omitted where this is not desirable, and likewise if preferable the automatic shifting means may be replaced by manually operable shifting means. These and other variations of the starting mechanism, together with changes in the form, details of construction and arrangement of parts, will now be apparent to those skilled in the art, and 5 may be made without departing from the spirit of the invention. Reference is therefore to be had to the appended claims for a definition of the 10 limits of the invention.

What is claimed is:

1. Inertia starting mechanism for internal combustion engines comprising an engine engaging member, an inertia element adapted for high speed rotation to store energy therein for cranking said engine, means including reduction gearing and a yieldable driving connection for drivably connecting said inertia element and said engine engaging member, an internal combustion engine for accelerating said inertia element, and means concurrently stopping said accelerating 20 engine and shifting said driving member to cranking position.

2. Starting mechanism for internal combustion engines comprising a driving member shiftable to engine engaging position, an inertia element driv- 30 ingly connected to said driving member and adapted for rotation to store energy therein, an internal combustion engine for accelerating said inertia element, driving connections between said accelerating engine and said inertia element, a 35 magneto drivably connected with a rotating part of said mechanism for supplying ignition current to said accelerating engine, and common means for interrupting said ignition current and shifting said driving member to engine-engaging 40 position.

3. Starting mechanism for internal combustion engines comprising a driving member adapted to be shifted to engine cranking position, an inertia element drivingly connected with said driving 45 member, means for accelerating said inertia element, a magneto for supplying ignition current to said engine to be started, and means for driving said magneto while said inertia element is being accelerated and means for insuring proper angular relation between said magneto driving means 50 and said accelerating means.

4. Starting mechanism for internal combustion engines comprising a driving member movable to engine engaging position, a rotatable inertia 55 element drivingly connected with said driving member, an internal combustion engine for accelerating said inertia element, means drivingly connecting said accelerating engine with said inertia element, and means for stopping said accelerating 60 engine when said driving member is moved into cranking engagement with the engine to be started.

5. Engine starting mechanism comprising a rotatable driving member movable to engine cranking position, a rotatable flywheel drivingly connected to said driving member, an internal combustion engine for accelerating said flywheel, means including a one-way driving connection for drivingly connecting said accelerating engine 65 with said flywheel, and means for stopping said engine when said driving member is moved to engine cranking position.

6. Starting mechanism for internal combustion engines comprising a driving member movable to engine cranking position, an inertia element driv-

ingly connected with said driving member, an internal combustion engine for accelerating said inertia element, means drivingly connecting said accelerating engine with said inertia element, and means operable at a predetermined speed of rotation of said inertia element to stop said accelerating engine, said stopping means being operable prior to disengagement of said driving member from said engine member. 5

7. Engine starting mechanism comprising a 10 driving member movable to engine cranking position, a rotatable flywheel drivingly connected with said driving member, an internal combustion engine for accelerating said flywheel, means including a one-way connection for drivingly connecting said accelerating engine with said flywheel, and means operable at a predetermined speed of rotation of said flywheel to stop said accelerating engine, said stopping means being operable prior to return of said driving member 20 from engine cranking position.

8. Starting mechanism for internal combustion engines comprising a driving member movable to engine cranking position, an inertia element drivingly connected with said driving member, an internal combustion engine for accelerating said inertia element, means drivingly connecting said accelerating engine with said inertia element, a magneto drivably connected with a rotating part of the mechanism for supplying ignition current to said accelerating engine, and means for disconnecting said magneto from said accelerating engine when said driving member is moved to engage said engine. 25 30 35

9. Engine starting mechanism comprising a driving member movable to engine cranking position, an inertia element drivingly connected with said driving member, an internal combustion engine for accelerating said inertia element, means drivingly connecting said accelerating engine with said inertia element, a magneto connected to supply ignition current to said accelerating engine, and means operable at a predetermined speed of rotation of said inertia element for moving said driving member and for disconnecting said magneto from said accelerating engine. 40 45 50

10. Engine starting mechanism comprising a driving member movable to engine cranking position, an inertia element drivingly connected to said driving member, an internal combustion engine drivingly connected with said inertia element for accelerating the latter, a magneto drivably connected with said accelerating engine and adapted to supply ignition current thereto, means operable when said driving member is moved to disconnect said magneto from said accelerating engine and connect said magneto to said engine to be started, and means for driving said magneto from said inertia element. 55

11. Starting mechanism for internal combustion engines comprising a driving member movable to engine cranking position, a flywheel drivingly connected to said driving member, an internal combustion engine drivingly connected to said flywheel for accelerating the same, a magneto drivably connected to said mechanism, switching mechanism for connecting said magneto to said accelerating engine and to said engine to be started, and means for shifting said switching mechanism when said driving member is moved. 60 65 70

12. Starting mechanism for internal combustion engines comprising a driving member movable to engine cranking position, a flywheel drivingly connected to said driving member, an in-

ternal combustion engine drivingly connected to said flywheel for accelerating the same, a magneto, switching mechanism for connecting said magneto to said accelerating engine and to said engine to be started, and means operable at a predetermined speed of rotation of said flywheel for moving said driving member and shifting said switching mechanism.

13. In engine starting mechanism, the combination of a driving member adapted to be shifted to engine cranking position, an inertia element drivably connected to said driving member, an internal combustion engine for accelerating said inertia element, and common means operable at a predetermined speed of rotation of said inertia element for shifting said member into engine-engaging position and stopping said accelerating engine.

14. In starting mechanism for internal combustion engines, in combination with a flywheel in which energy is stored, a magneto and an ignition circuit fed therefrom, means for storing energy in said flywheel and at the same time actuating said magneto, and means responsive to the establishment of driving connection between the flywheel and engine to render said ignition circuit inoperative.

15. In starting mechanism for internal combustion engines, in combination with a flywheel in which energy is stored, a magneto and an ignition circuit fed therefrom, means for storing energy in said flywheel and at the same time actuating said magneto, a circuit controlling member in said ignition circuit, and means for actuating said circuit controlling member and at the same time establishing driving connection between the flywheel and engine.

16. In starting mechanism for internal combustion engines, in combination with a flywheel in which energy is stored, a magneto and an ignition circuit fed therefrom, means for storing energy in said flywheel and at the same time actuating said magneto, a circuit controlling member in said ignition circuit, and means for actuating said circuit controlling member and at the

same time establishing driving connection between the flywheel and engine, said last named means including a shaft and sleeve normally rotatable as a unit with said flywheel but relatively rotatable to a limited extent after a predetermined degree of acceleration of said flywheel.

17. In an engine starter, in combination, a driving member adapted to be engaged with and crank a member of the engine to be started, a flywheel connected through reduction gearing with the driving member, means to receive a charge of explosive, rotatable current-generating means to ignite the explosive, means actuated by the expanding products of explosion to bring said flywheel up to high speed, and means responsive to the attainment of such high speed to mesh said driving member with said engine member.

18. In an engine starter, in combination, a driving member adapted to be engaged with and crank a member of the engine to be started, a flywheel connected through reduction gearing with the driving member, means to receive a charge of explosive, manually rotatable means to ignite the explosive, means actuated by the expanding products of explosion to bring said flywheel up to high speed, and means responsive to the attainment of such high speed to mesh said driving member with said engine member.

19. In starting mechanism for internal combustion engines, in combination with an engine engaging member, actuating means for said engine engaging member comprising a starting engine which is also of the internal combustion type and includes a rotatable crankshaft and a magneto, a gear train operatively connecting said crankshaft with both said magneto and engine engaging member, means for feeding current generated in said magneto to both said internal combustion engines, said last named means including a switch for diverting the current from the starting engine to the engine to be started, and means for operating said switch in response to movement of said engine engaging member to the engine engaging position.
